[57] CLAIM

The ornamental design for a luggage zipper lock, as shown and described.

DESCRIPTION

FIG. 1 is a perspective view of a luggage zipper lock showing my new design, it being understood that the broken lines are for illustrative purposes only;

FIG. 2 is an enlarged top plan view thereof;

FIG. 3 is an enlarged side elevational view thereof, the opposite side being substantially a mirror image of the side shown;

FIG. 4 is an enlarged front elevational view thereof; and

FIG. 5 is an enlarged rear elevational view thereof.
